UNITED STATES PATENT OFFICE.

GEORGE T. HADLEY, OF SAN FRANCISCO, CALIFORNIA.

PROCESS FOR THE REINFORCEMENT OF GAS-MANTLES OF THE INCANDESCENT TYPE FOR ILLUMINATING PURPOSES.

1,123,869.

Specification of Letters Patent.

Patented Jan. 5, 1915.

Application filed December 1, 1913. Serial No. 804,130.

To all whom it may concern:

Be it known that I, GEORGE T. HADLEY, a citizen of the United States, residing at San Francisco, in the county of San Francisco and State of California, have invented new and useful Improvements in Processes for the Reinforcement of Gas-Mantles of the Incandescent Type for Illuminating Purposes, of which the following is a speci-
10

My invention relates to the class of processes for the reinforcement of gas mantles of the incandescent type for illuminating purposes. Its object is to increase the durabil-
15 ity, and thereby prolong the life and service of the mantle.

My invention consists in reinforcing the weakest or most vulnerable portions of the mantle with aluminum, the metallic alumini-
20 num being reduced to a non-fusible non-com-
bustible metallic matte by the action of a carboniferous reducing agent when heat is applied. This matte is composed largely of carbonized aluminum and by the oxidizing
25 heat of combustion, a very slow, natural oxidation of the exposed edges of the matte takes place during the life of the mantle, the retarding of which measures the utility of the deposit as a metallic reinforcement.
30 It has a very wide latitude in its qualities of expansion and contraction adapting it for combination with materials of a different character, without the rupture or disintegra-
35 tion which would otherwise be evident in such combinations when subjected to great differences in temperature.

Reference to the accompanying drawings will indicate the particular portions of the upright and inverted mantles amenable to
40 my process of reinforcement.

Figure 1 is a side elevation partly broken away, of a mounted upright mantle, showing the application of my reinforcing process to both ends of the mantle, and its relation
45 with the metal cap. Fig. 2 is a view showing the application of my process solely to the lower portion of the upright mantle. Fig.
50 3 is an enlarged side elevation partly broken away, of an inverted mantle, showing its reinforcement at and around the mantle ring and binding cord.

Of Fig. 1, the numeral 1 indicates the body portion or walls of the mantle, at 2 and 3, I have indicated the reinforced por-
55 tions; 4 is the usual form of metal cap de-

signed to fit over the Bunsen tube of the ordinary gas burner, the cap being supplied with the usual gauze 5 and double wire support for the mantle. The reinforced portion shown at 2 may include the loop 6 and to 60 minimize its encroachment on the lighting field, should terminate at or near the ends of the small folds formed by the loop and draw string. The reinforced portion shown at 3 should be of extent taking up approxi-
65 mately half the perpendicular space there may be in that portion of the skirt of the mantle extending below the gauze 5 when the mantle is in pendent position on its support. This is to allow for the shrinkage that 70 usually takes place in the mantle in course of everyday use, and which if not provided for, would gradually bring the reinforced portion above the top of the cap, any such encroachment would diminish the luminous 75 field to a like extent.

The form shown in Fig. 2, includes the reinforcement of the lower portion of the mantle only. This form of reinforcement would be of special utility in the cheaper 80 grades of mantles, or in a light weight mantle not likely to sag with its own weight during combustion.

In Fig. 3, I show the application of my process to the inverted mantle; 7 indicates 85 the usual magnesia ring common to the inverted mantle, 8 the binding cord, and at 9 I have indicated the reinforcement at and around the mantle ring and binding cord.

My aluminum process of reinforcement 90 and its application in practice, may be described as follows: The metallic aluminum may be carbonized before its application to the mantle, and may then be applied to the parts by the use of any liquid medium suit-
95 able for the purpose; however, in its pre-
ferred form the process provides for the carbonization of the aluminum after its ap-
plication to the mantle, by ignition, either by design or by the usual ignition of the 100 mantle when put in combustion. In the latter method the form of metallic aluminum most suitable and that preferred being aluminum powder, commonly known in the decorative arts as aluminum bronze. To the 105 aluminum powder may be added any gum or resin, or a combination of them, suffi-
ciently rich in carbon to act as a reducing flux for the aluminum when heat is applied, a suitable combination for the purpose may 110

consist of gum turpentine and caoutchouc equal parts, to which may be added sufficient chloroform to act as a solvent and merger, the desired consistency being obtained by the 5 addition of a quickly drying dilutent, such as naphtha or benzin.

The proportion of reducing agent required to a given quantity of the aluminum powder, depends on the particular reducing 10 agent employed, the reducing power differing in each. Either of those mentioned, in proportional amount, should equal approximately, fifty per cent. (50%) of the aluminum powder employed, by weight, to which 15 may be added sufficient dilutent to produce the consistency desired, the latter depending upon the weight of deposit, or thickness, of the resulting matte required. However, the preparation should be sufficiently liquid to 20 enter the fabric of the mantle, thoroughly permeating the fiber with the aluminum.

The prepared aluminum may be applied to the parts of the mantle to be reinforced, either before the mantle is collodionized, or 25 after, either by dipping or by other means found convenient and most suitable.

If the aluminum is applied to the mantle before the mantle is collodionized, the mantle may then be collodionized or dipped into 30 its usual protective bath, or, the reinforced portions, (which before ignition are inflammable) may be ignited, and the superficial carbon, deposited on the mantle by the flames of the reducing agent, may be removed 35 by re-ignition over a Bunsen tube, and the mantle then collodionized. The advantage of this procedure lies in the reduction to a minimum, of the smoke produced when the mantle is first ignited by the consumer. 40 However, by this prior ignition, the beautiful silverlike appearance of the part reinforced is lost to a large extent, due to the aluminum being reduced to a matte, and if appearances are sought at the expense of the consumer, ("expense", by reason of the inevitable smoke imposed,) the non-ignition method is much to be preferred.

The light producing qualities of the incandescent gas mantle, are seldom exhausted 50 before the fabric of the mantle has been shattered or ruptured by other means than those due to combustion. This applies to the different forms of gas mantles constructed of fibrous materials, including the upright mantle, which is commonly called the "cap mantle", and the inverted type of mantle. The weak points, or the particular portions 55 most subject to premature disintegration, and the general causes therefor, may be to a considerable extent defined as follows: A frequent cause of destruction in the cap mantle, is the abrasion of the skirt, or free end of the mantle, by its contact with the metal cap. This is most noticeable in street 60 lights where the lamps are subjected more

or less constantly to vibration caused by air currents. Hanging lamps and chandeliers also subject the mantles to movement and vibration. A reinforcement of this portion of the mantle prevents abrasion and materially adds to its longevity. Another cause of early destruction in the cap mantle is the breakage of the fibers of the upper portion of the mantle immediately below the loop, and also at or near the terminals of the 70 small folds formed by the draw string. This breakage is mainly caused by the weight of the suspended mantle and the impinging gas. At a white heat the mantle fiber is very soft and gives way under the 75 double strain. The proper reinforcement of this portion of the mantle, reduces the breakage at this point to a minimum.

In the inverted mantle the portion most frequently affected is at or near the mantle 80 ring. This is partly due to the difference in expansion and contraction of the mantle fiber and binding cord and the mantle ring. The variation in tension frequently cutting the mantle fiber or breaking the cord, the 85 mantle soon leaving the ring. In addition to this the entire weight of the mantle, and practically all the vibration to which the mantle may be subjected, is concentrated at this point. A proper reinforcement in this 90 part, including in its scope the binding cord by which the mantle is bound to the mantle ring, results in greatly increased durability 95 of the mantle. It is pertinent, that in the reinforcement of the inverted mantle, the 100 permeating and adhesive qualities of the aluminum process as here set forth are of particular utility in effecting a perfect union between the mantle and the mantle ring, practically sealing the mantle to the ring 105 and partaking of the qualities of expansion and contraction of both when heat is applied, without rupture. This is noticeable to the extent that only for the convenience it affords in placement of the mantle, the 110 binding cord could be dispensed with entirely, the aluminum matte unassisted forming an efficient binder.

Any reinforcement of the inverted mantle 115 below the mantle ring to neutralize the impingement of the gas, should be of a very light nature. Any considerable amount of the non-incandescent material would encroach on the lighting field. This can be partly overcome by salting the aluminum reinforcement with the salts of incandescence.

I do not wish to be limited to the application of the process, at any particular stage of the process of manufacture either of the mantle or of the process itself, for it is evident that the aluminum could be converted to any of the forms included in the process, before its application, and afterward applied to the parts with practically the same results. The process being largely metamor- 120 125 130

phic in its nature, practically precludes its limitation to one particular form of the metal, the natural ignition and combustion of the mantle changing the metal to other forms automatically, the first of which may be termed carbonized aluminum.

The particular form of carbon employed in the process may be said to be governed principally by its ready and uniform combining qualities when mixed with the aluminum and a suitable fluid medium for the purpose of its application to the mantle. Any of the carbons or carboniferous materials such as charcoal, graphite, guncotton, or any of the volatile carboniferous oils containing sufficient carbon, are available, and when properly combined with the metallic aluminum serve the required purpose. Nor do I wish to be circumvented by an aluminum process containing low percentages of other metals, because it is common for commercial aluminum (which is always in a more or less impure state) to contain small percentages of other metals, tin and antimony being frequently added for a brightening or non-tarnishing effect. Mica used as an adulterant, is often found in aluminum powder. The addition of mica in considerable quantities does not interfere with the process.

Having pointed out the wide scope to which the aluminum process may be, inadvertently or otherwise modified, without departing from its principle or its ultimate effect, I wish to be protected in the process.

in so far as aluminum may be the predominating element or power of efficiency.

By comparison with other processes for a like purpose, my aluminum process may be said to advantageously differ or excel, in the following particulars: permanency; efficiency; cheapness; and in artistic appearance. The latter being an advantage of importance from a commercial standpoint. The use of the process in the reinforcement of gas mantles results in a maximum of candle-power hours (due to a better average of unimpaired condition in the mantle) and a consequent saving in cost to the consumer.

I claim:

1. An incandescent mantle having a portion of its walls reinforced with a compound containing metallic aluminum and carbon.
2. An incandescent mantle having a portion of its walls reinforced by the application thereto of a compound consisting of metallic aluminum and carboniferous gum.
3. An inverted mantle of the incandescent type having in that portion of its walls encircling the mantle-ring a compound of metallic aluminum and carboniferous gum for the purpose of reinforcement in its attachment thereto.

In testimony whereof, I have hereunto set my hand in the presence of two subscribing witnesses.

GEORGE T. HADLEY.
